[57] CLAIM

The ornamental design for a retractable detail brush with cap, as shown and described.

DESCRIPTION

FIG. 1 is a front elevational view of a retractable detail brush with cap showing my new design with the bristles retracted in the handle in stored position, the rear view being a mirror image;

FIG. 2 is a top view thereof;

FIG. 3 is a left end view thereof;

FIG. 4 is a right end view thereof;

FIG. 5 is a bottom view thereof;

FIG. 6 is a front perspective view thereof;

FIG. 7 is a front elevational view thereof with the right end bristles in the extended position; and,

FIG. 8 is a front elevational view thereof with the cap removed and the left end bristles in the extended position, the cap being omitted for ease of illustration only.
